UNITED STATES PATENT OFFICE

PAUL GNIFKE, OF MILWAUKEE, WISCONSIN, ASSIGNOR TO RAILWAY ELECTRIC MANUFACTURING CO., OF MILWAUKEE, WISCONSIN.

CALL-BOX.

1,309,569.

Specification of Letters Patent.

Patented July 8, 1919.

Application filed July 16, 1917. Serial No. 180,707.

To all whom it may concern:

Be it known that I, PAUL GNIFKE, a subject of the Emperor of Germany, residing at Milwaukee, in the county of Milwaukee and State of Wisconsin, have invented a certain new and useful Improvement in Call-Boxes, of which the following is a full, clear, concise, and exact description, reference being had to the accompanying drawings, forming a part of this specification.

My invention relates to signaling systems and more particularly to call boxes used in step by step signaling systems. My invention is more particularly of use in connection with substation selectors such as shown in general in the patent to Lademan, No. 1,120,207, dated December 8, 1914, and such as shown more particularly and in a modified form in my co-pending application Serial No. 180708, filed July 16, 1917. The structure shown in the patent to Lademan above cited represents an alternating current escapement type substation selector in which the step by step element is arranged to have resting positions corresponding to each alternation of alternating current.

My invention concerns itself in providing a call box to selectively call a modified selector of the type shown in the Lademan patent, this modified form being set forth in my said co-pending application. My improved modified selector has provision whereby all of the other stations on the party line may be locked out so that the party called may use the line exclusively for telephonic or similar purposes.

My invention herein concerns itself with the provision of a call box adapted to operate such a modified selector through the agency of which all stations on the line with the exception of the predetermined station are locked out. In order to carry out my invention I arranged the substation selectors in such a way that more than one impulse (or cycle if desired) of the alternating current intervenes between each succeeding station. Thus if it requires two alternations or one cycle to call the station No. 1, then the system will be so arranged that it would require two additional alternations to call station No. 2. There is thus an intermediate position of the step by step element, namely that due to the sending of one additional impulse or alternation which can

be used to advantage, and this is utilized for lock out purposes. Thus, if it is desired to call station No. 4, for instance, and lock out all of the remaining stations, then in accordance with the above discussion four cycles of alternating current are transmitted to the line whereby the signal at station No. 4 is operated. If one additional alternation (not cycle) of alternating current is transmitted to the line, this additional impulse will not be sufficient to have the selector at station No. 5 respond as it requires one complete cycle to bring the selector at the next following station into operative position, as before stated. Thus this additional impulse or alternation sets the selector at the called station into such a condition that that particular station has its telephone or other substation equipment connected to the line, whereas the intermediate positions occupied by the selectors at the remaining stations prevent connection of their substation equipments to the line. If, on the contrary, it is desired to have all of the substation equipments connected to the line, then the calling device after having been operated to transmit a call for a predetermined station is continued in its operations so that the step by step elements at the selectors complete their cycle of movement to their starting position, at which time all of the substation talking or similar equipments are connected to the line, it being remembered however that the predetermined station only has its signaling device activated.

In the particular form of my invention herein I have assumed that two cycles shall intervene between succeeding stations, thus that it requires two cycles of alternating current to send a call for station No. 1, four cycles for station No. 2, and so on. I then use for the locking out impulses one complete cycle of alternating current, which under these circumstances is not sufficient to step up the selector at the station succeeding the one which has been called. This one cycle of alternating current can thus be used for the lock out purposes, as previously explained.

My invention herein concerns itself particularly with the provision of a calling device or call box so arranged that a control element thereof may be selectively set so that the calling device may transmit the re-

105

110

quired impulses to select a predetermined station. The calling device then has my improved facilities whereby it may be actuated to transmit automatically the required additional cycle for lock out purposes.

I will explain this particular form which my invention may take more in detail by referring to the accompanying drawings, in which—

Fig. 1 is a front view of a call box constructed in accordance with my invention;

Fig. 2 is a similar view showing the call box control element in an intermediate position;

Fig. 3 is a rear view of the cover plate of the call box on which all of the operating equipment is mounted;

Fig. 4 is a detail of the impulse sender;

Fig. 5 is a sectional view on line 5—5 of Fig. 3;

Fig. 6 is an enlarged fragmentary view in elevation of the coöperating elements which restrain the control element of the call box in the position shown in Fig. 2;

Fig. 7 is a side view of the cover plate of the call box with the equipment mounted thereon;

Fig. 8 is a view similar to Fig. 3 showing the calling device in its neutral zero position, and

Fig. 9 is a perspective view of some of the elements shown in Fig. 6.

My improved calling device has its equipment mounted upon a cover plate 10 which is mounted upon the box 11 so that when the cover is closed the greater proportion of the equipment is accommodated interiorly of the box for reasons well understood.

This cover plate pivotally carries a shaft 12 extending through said cover plate, and this shaft carries forwardly of the cover plate a selecting disk 13, which disk is fixedly mounted to said shaft. Rotatably mounted

on said shaft is the spoke 14 provided with the finger piece 15, which finger piece has the projecting stem 16 adapted for insertion into the holes 17 of the disk 13. The spoke 14 also carries a tail piece 18 fixedly secured thereto, which tail piece coöperates with a contact lever 19 under certain conditions, and which tail piece likewise has a cut-away portion 20 for purposes which will presently appear. The disk 13 also carries

a lug 21, which, when the disk is in the particular position shown in Fig. 1, coöperates with the contact control element 19 as will presently appear. The holes are numbered as shown, and when it is desired

to initiate a call for a predetermined station, say station No. 14, for instance, then the finger 16 by manipulation of the finger piece 15 is pulled outwardly and the spoke 14 rotated so that the finger piece 15 is over

the hole No. 14, whereupon it is inserted

in that hole. The disk 13 together with the then attached spoke 14, finger piece 15 and tail piece 18 are then rotated clockwise (Fig. 1) into a given limiting position (which limiting position is fixed by having a pin 22 extending downwardly of the disk 13, against the stop 23 projecting upwardly from the cover plate 10). It will be seen that this requires practically a rotation of the disk 13 throughout a movement of substantially 360 degrees so that the hole marked No. 2 is again to the left of the circuit control element 19. After the setting device has been rotated into that position preparatory to sending a call the operator releases his hold upon the finger piece 15 and automatic mechanism provided rearwardly of the plate restores the shaft 12 carrying the disk 13 contra-clockwise. This contra-clockwise movement is continued until the knurled finger piece 16 engages a toothed stop 24. This stop 24 is pivotally mounted upon a stem 25 and retracted by a spring 26. There is a further similarly mounted toothed stop 27 retracted by a spring 28, this stop 27 being also pivotally mounted on a similar stem. Both of these stops are in the path of the knurled finger 15. It will be seen from an inspection of Fig. 2 that the tail piece 18 when it engages the contact control element 19 moves it outwardly so that it occupies the position shown in Figs. 1, 2 and 3. In this position the springs 29, 30, 31 and 32 which are controlled by this element 19 are in a non-circuit closing condition. These springs are all insulatedly mounted and are actuated by the element 19 in the customary manner. These springs 29, 30, 31 and 32 control the connection of the pivotally mounted pole changing device 33 with the line circuit over which the impulses are to be transmitted. The connecting wires leading from this pole changing device have their continuity controlled by the springs under the control of the element 19. It will thus be understood that after the disk 13 has been moved by the operator clockwise into the position it initially occupies preparatory to the transmitting of a signal, the said disk is rotated contra-clockwise automatically by mechanism presently to be explained. This automatic movement rotates the disk and during this rotation impulses are being transmitted to the line circuit by reason of the operation of the pole changing device 33 and by reason of the fact that neither the elements 18 nor 21 are engaging the element 19. The impulses are sent during the course of this backward rotation of the element 13 until the tail piece 18 engages the element 19. During the continuance of the rotational movement of the disk 13 no further impulses are being sent to the line by reason of the disconnection of the line 130

circuit from the springs under the control of the element 19.

By referring to Fig. 2 it will be found that the knurled finger piece 16 has engaged the stop 24 before the tail piece 18 has had time to complete its passage past the control element 19. The selectors with which this call box co-operates and which are set out fully in the said Lademan patent are of such a nature that after the sending of impulses, if the connection of the current to the line be discontinued, the selector at the selected station automatically causes the actuation of the substation signal. The substation signal at the station No. 14 is thus operating during the time that the tail piece 18 is engaging the element 19. If, now, it is desired to lock out all of the substations on the line excepting the substation 14, then it is necessary to transmit an additional cycle of alternating current, but no more, and this is accomplished by the operator rotating the finger piece 15, whereupon the knurled finger piece 16 engages the teeth of the element 24 with which it is in engagement, thus rotating this pivotally mounted element to a position where it is possible for the finger piece 16 to continue past this stop. The disk 13 together with the elements attached to it then continues to rotate contra-clockwise until the finger piece engages a stop 27. In the meantime the connection to the line of the pole changing element 33 has been restored due to the cut away portion 20 of the tail piece 18 which has permitted the control element 19 to re-establish contact between the springs under its control, but only during a period long enough to permit of the transmitting of one complete cycle. Now, should it be desired to maintain this relation of having all of the substations locked out except station No. 14 then no further actuation of the disk 13 takes place. The moment the conversation is completed, however, the finger piece 15 is again rotated to swing the stop 27 out of its path, whereupon the disk 13 continues its automatic rotation contra-clockwise back to its starting position with the projection 22 on the left hand side (Fig. 1) of the stop 23 and with the lock 21 in position against the control element 19, thus breaking the connection of the pole changer 33 with the line circuit. It will be noted that during this movement of the disk 13 back to its starting position, and up until the time that the lock 21 engages the control element 19, the connection between the pole changer and the line circuit is restored so that impulses are being transmitted over the line circuit to carry all of the substation step by step elements around their complete cycle to their initial or starting position.

My invention concerns itself here particularly with the provision whereby the call-

ing device is enabled accurately to send such an impulse or impulses carefully timed to bring the substation selectors into their locked out position and to bring the substation apparatus of the desired station into its active condition.

By referring more particularly to Fig. 3 it will be noted that the shaft 12 carries the gear wheel 50 fixedly secured thereto which through the intermediation of the gear wheel 36 and additional gears is associated with the shaft 37. This shaft carries a cam 38, which cam by engaging the arms 39 and 40 of the pole changer 33 causes the oscillation of this pole changer, this pole changer being pivotally mounted upon the stud 41. A governor 42 controls the speed of operation of the device in answer to the pull of the main spring 43. The shaft 12 carries the finger 44 which co-operating with the lever 45 accurately positions the zero position of the pole changer. This is done through the agency of the toe 46 forming part of the lever 45 which is thrust into the path of the finger 47 which is carried by the shaft 37. When the shaft 12 comes back to its zero position the projection 44 engages a toe 48, thereby swinging the element 45 clockwise (Fig. 3) into the path of the finger 47. The tail piece 18 is continued beyond the cut away portion 20, as shown, so that the tail section 49 thereof engages the element 19 during the time that the finger 16 is against the stop 27.

It will be understood that as the shaft 12 is originally rotated during the setting operation of the disk 13 that the spring 43 is wound up and that it thereupon unwinds to drive the shaft 12 back into its starting position, the speed of which rotation is controlled by the governor 42. It will also be understood that during the setting movement of the element 13 none of the impulses from the pole changer 33 are transmitted to the line as the pawl 49 rides over the wheel 50 during that operation and by reason of the fact that the wheel 36 which carries this pawl 49 is loose upon the shaft 12. Pole changer arms 39 and 40 which at the same time are the contact carrying elements of the pole changer are mounted upon the insulating block 51 which in turn is pivotally supported upon the stud or shaft 41. This structure consisting of the elements 39, 40, and 51 is then oscillated by the cam 38 as said cam is rotated due to its fixed mounting upon the shaft 37.

From what has been thus described the nature of my invention will be readily apparent to those skilled in the art. Having however thus described one form which my invention may take, what I claim as new and desire to secure by Letters Patent is:

1. In a calling device for selective signaling systems the combination with an impulse

- transmitting element, means adapted to be selectively set in accordance with the call for any predetermined station and movable to control the actuations of said impulse transmitting element, a stop interposed in the path of movement of said setting means to arrest the movement of said setting means at a given position in its movement, a second stop adapted to arrest said setting means a second time, and means to release said setting means from said first aforesaid stop and permit it to travel to the second stop.
2. In a calling device for selective signaling systems the combination with an impulse transmitting element, means including a finger piece adapted to be selectively set in accordance with the call for any predetermined station and movable to control the actuations of said impulse transmitting element, a stop interposed in the path of movement of said setting means to arrest the movement of said setting means at a given position in its movement, a second stop adapted to arrest said setting means a second time, and means to release said setting means from said first aforesaid stop and permit it to travel to the second stop.
3. In a calling device for selective signaling systems the combination with an impulse transmitting element, means including a finger piece adapted to be selectively set in accordance with the call for any predetermined station and movable to control the actuations of said impulse transmitting element, a stop interposed in the path of movement of said setting means to arrest the movement of said setting means at a given position in its movement, a second stop adapted to arrest said setting means a second time, and means controlled by said finger piece to release said setting means from said first aforesaid stop and permit it to travel to the second stop.
4. In a calling device for selective signaling systems the combination with an impulse transmitting element, means including a finger piece adapted to be selectively set in accordance with the call for any predetermined station and movable to control the actuations of said impulse transmitting element, a stop interposed in the path of movement of said setting means to arrest the movement of said setting means at a given position in its movement, a second stop adapted to arrest said setting means a second time, and means controlled by said finger piece to release said setting means from said first aforesaid stop and permit it to travel to the second stop, said last aforesaid means including interlocking elements between said finger piece and said first aforesaid stop.
5. In a calling device for selective signaling systems the combination with an impulse transmitting element, means adapted to be selectively set in accordance with the

call for any predetermined station and movable to control the actuations of said impulse transmitting element, a stop interposed in the path of movement of said setting means to arrest the movement of said setting means at a given position in its movement, a second stop adapted to arrest said setting means a second time, means to release said setting means from said first aforesaid stop and permit it to travel to the second stop, and additional means movable with said finger piece whereby the number of effective impulses transmitted by said impulse transmitting element during the movement from the first stop to the second are controlled.

6. In a calling device for selective signaling systems the combination with an impulse transmitting element, means including a finger piece adapted to be selectively set in accordance with the call for any predetermined station and movable to control the actuations of said impulse transmitting element, a stop interposed in the path of movement of said setting means to arrest the movement of said setting means at a given position in its movement, a second stop adapted to arrest said setting means a second time, means to release said setting means from said first aforesaid stop and permit it to travel to the second stop, and additional means movable with said finger piece whereby the number of effective impulses transmitted by said impulse transmitting element during the movement from the first stop to the second are controlled.

7. In a calling device for selective signaling systems the combination with an impulse transmitting element, means including a finger piece adapted to be selectively set in accordance with the call for any predetermined station and movable to control the actuations of said impulse transmitting element, a stop interposed in the path of movement of said setting means to arrest the movement of said setting means at a given position in its movement, a second stop adapted to arrest said setting means a second time, means controlled by said finger piece to release said setting means from said first aforesaid stop and permit it to travel to the second stop, and additional means movable with said finger piece whereby the number of effective impulses transmitted by said impulse transmitting element during the movement from the first stop to the second are controlled.

8. In a calling device for selective signaling systems the combination with an impulse transmitting element, means including a finger piece adapted to be selectively set in accordance with the call for any predetermined station and movable to control the actuations of said impulse transmitting element, a stop interposed in the path of movement of said setting means to arrest the

movement of said setting means at a given position in its movement, a second stop adapted to arrest said setting means a second time, means controlled by said finger piece 5 to release said setting means from said first aforesaid stop and permit it to travel to the second stop, said last aforesaid means including inter-locking elements between said finger piece and said first aforesaid stop, and 10 additional means movable with said finger piece whereby the number of effective impulses transmitted by said impulse transmitting element during the movement from the first stop to the second are controlled.

15 9. In a calling device for selective signaling systems the combination with an impulse transmitting element, means including a movable finger piece adapted to be selectively set in accordance with the call for any 20 predetermined station, and movable to control the actuations of said impulse transmitting element, and means controlled by said finger piece for arresting the movement of said first aforesaid means at two positions 25 during its signal impulse transmitting movement.

10. In a calling device for selective signaling systems the combination with an impulse transmitting element, means adapted 30 to be selectively set in accordance with a call for any predetermined station and movable

to control the actuations of said impulse transmitting element, said means having a plurality of control positions spaced to represent two or more impulses respectively of 35 said impulse transmitting element, each control position representing a call for a given substation, and means whereby said impulse transmitting element is actuated to send a less number of impulses than those represented by the spacings between said control positions.

11. A calling device for selective signaling systems having an impulse transmitting element, means adapted to be selectively set 45 in accordance with a call for any predetermined station to control the actuations of said impulse transmitting element, said means having a plurality of control positions spaced to represent two or more impulses respectively of said impulse transmitting element, each control position representing a call for a given station, and means for transmitting a different number of impulses than those represented by the spacings between 50 said control positions.

In witness whereof, I hereunto subscribe my name this 28th day of June, A. D. 1917.

PAUL GNIFKE.
